UNITED STATES PATENT OFFICE.

ROBERT B. COLEMAN, OF LOS ANGELES, CALIFORNIA.

COMPOSITE STICK.

1,310,004.

Specification of Letters Patent.

Patented July 15, 1919.

Application filed August 5, 1916. Serial No. 113,362.

To all whom it may concern:

Be it known that I, ROBERT B. COLEMAN, a citizen of the United States, residing at Los Angeles, in the county of Los Angeles 5 and State of California, have invented certain new and useful Improvements in Composite Sticks, of which the following is a specification.

This invention relates to improvements in composite articles, and particularly to composite sticks, briquets or commodities, of waste material, or comminuted or other similar substances, such as sawdust, shavings, chips, or other materials, which are compressed and shaped into any desired form 10 and are provided with a suitable holding or binding means, the said binding means being so applied that expansion in the materials compressed due to any cause will be accommodated without breaking or injuring 15 the binding means.

It is an object of the invention to provide a composite article or stick with a binding means having a slack portion therein adapted 20 to permit the materials to expand without breaking the binding means.

It is also an object of the invention to provide a composite stick of sawdust, shavings, chips or other loose materials, to which 25 is applied binding wires having a slack portion left therein to accommodate the swelling and expansion of the materials as for instance when they are wet, without the danger of snapping and breaking the wires.

30 In the accompanying drawing:

Figure 1 is a perspective view of a composite article made and bound in accordance with the present invention.

Fig. 2 is a longitudinal central sectional view 35 through the same, showing binding wires in position for holding the same in compact form, the wires being in side elevation.

Fig. 3 is a side elevation of one portion 40 of a composite member and a portion of another, showing the binding wires drawn together between them and twisted to fasten the materials in place.

Fig. 4 is a sectional view through one of 45 said composite articles or sticks.

Composite articles of various kinds and particularly of waste materials, which are adapted to be compressed and formed into composite articles, sticks, briquets or the like for use as fuel or other purposes, have heretofore been made, and shavings, saw-

dust, chips and the like have been heretofore pressed in stick form, and bound with wires for holding them in place. Such commodities however, have always been so bound 60 that the wires or other binding means were drawn snug and tight upon the materials with the result that if the said materials become wet or otherwise affected, so as to become swollen or expanded, the wires would 65 snap and become loose, whereby the materials were no longer held in position, to be properly usable as fuel or similar purposes. It is the purpose of this invention to be able to compress, shape and bind such materials 70 so that expansion will be properly allowed for and cannot destroy the effectiveness of the compressed substances as a fuel.

The details and features of the invention will now be more specifically described, reference being had to the drawing in which 75 1 indicates an article or stick of compressed materials and 2, kerfs or grooves formed in the sides thereof. Binding means in the form of wires 3 and 4 are illustrated for 80 holding the composite stick in its compressed form. The wires may be secured together in any desired manner but are preferably twisted as at 5 and 6 to secure them at the opposite ends of the article. In order to 85 accommodate the swelling or expanding of the compressed materials, as for instance when they become wet, a slack portion is formed in the wires at any suitable point of sufficient size to permit of enough expansion 90 without the danger of breaking or snapping the wires. It is usually sufficient to form a slack space as at 7, in the wires at one end of the stick, though of course it might be located at any point in the length of the 95 wires and at either end of the stick, without departing in the least from the spirit of the invention. The materials compressed are preferably brought into a somewhat compact form in a suitable machine or mechanism 100 designed for the purpose. Such a machine has been set forth in an application filed by me, Aug. 5, 1916, 113,363 now Patent 1,260,514, March 26, 1918, comprising means for continuously forcing the materials to be compressed into and through a forming die in a continuous stick. The stick is broken off in suitable lengths, the wires being pulled out between them. A suitable twisting and cutting mechanism is then 110 caused to engage the wires and twist them as shown in Fig. 3 of the drawing, after

which the wires are cut at a point intermediate the length of the twisted part. The wires are usually twisted so that a vacant or slack space as at 7 is left between them, 5 usually at one end of a stick, since that is generally sufficient. The length of the slack portion may be varied as desired and in accordance with the character of the materials compressed.

10 The compressing of certain materials in this manner forms an excellent fuel out of various waste products. When compressing such materials as shavings, sawdust, chips and the like, the wire is preferably more or 15 less deeply embedded in the sides of the stick, the grooves 2 being made to accommodate the wires. In burning a fuel of this kind, the shavings and sawdust will soon curl out from under the wires and split and 20 become loose too readily if the wires are not properly embedded in the sides of the stick. For this reason the use of the deep kerfs with the wires laid therein, is important in producing a fuel which will not disintegrate 25 and burn too rapidly. With the fuel of this kind also if any of it becomes wet, the wood will swell and expand to such an extent as to snap the wires unless a slack space as 7 is provided. This has been one 30 of the chief difficulties in producing sticks or briquets of compressed materials for fuel heretofore. If the wires break in this manner, the fuel becomes of no value for it will all fall apart immediately upon being 35 put into the fire and will burn too rapidly to be of any value as a fuel.

In machines which have been adapted for compressing articles, materials and waste substances in a stick or briquet form, the 40 materials which have to be tightly packed together, are frequently compressed too tightly within the wires, and as no slack of room has been left within the wires, a large

percentage of the bound sticks have been found to break their wires before they could 45 be used as fuel, thus destroying their quality as a fuel. The providing of sticks or blocks of compressed material with a slack space in their binding wires also insures their being held together in the fire a 50 sufficient length of time. Where no slack is left the wire, the heat from the fire when the fuel is pressed therein, quickly ruptures the wire and permits the materials to fall apart too soon. The bound article of the 55 invention obviates all these difficulties.

A composite stick of this kind makes it possible to use all kinds of waste material for the purposes of fuel. Especially can sawdust and shavings be made into fuel as 60 can also waste straw with chaff and weeds, hay, etc., be used and compressed so as to form an excellent fuel. It will of course be understood that the kinds of materials of which such a composite stick can be made 65 are not limited and that many kinds of materials and waste matter can be used within the scope of the invention.

What is claimed is:

An article of manufacture comprising a 70 fuel stick made up of loose materials pressed together into form and having longitudinally disposed retaining grooves in its sides, and binding wires around said stick, longitudinally thereof, in said grooves, and 75 twisted together at the end of said stick, at a space therefrom, whereby to leave a definite slack space between the end of the stick and the wires for expansion purposes, substantially as shown and described. 80

In testimony whereof, I have hereunto set my hand, in presence of two witnesses.

ROBERT B. COLEMAN.
